CLAIM

The ornamental design for the graphic pattern for a portion of a shoe upper, as shown and described.

DESCRIPTION

FIG. 1 is a right side elevational view of a graphic pattern for a portion of a shoe upper showing my new design;

FIG. 2 is a left side elevational view; and

FIG. 3 is a rear elevational view.

The broken line showing of the remainder of the shoe upper and of the sole is for illustrative purposes and forms no part of the claimed design.

FIG. 1
